DALE W. DEAN, OF WILKINSBURG, PENNSYLVANIA, ASSIGNOR TO WESTINGHOUSE ELECTRIC & MANUFACTURING COMPANY, A CORPORATION OF PENNSYLVANIA

CONTROL SYSTEM

Application filed September 30, 1927. Serial No. 222,965.

My invention relates generally to systems of control and particularly to control systems for rolling mills and the like.

The object of my invention, generally stated, is to provide a control system which shall be simple and efficient in operation and readily and economically manufactured and installed, and further to provide means for rendering the speed adjustment of the component parts of a rolling mill equipment more nearly automatic than has heretofore been possible.

A more specific object of my invention is to provide for maintaining a definite speed relation between the reducing rolls and the roll tables, throughout a comparatively wide range of operation.

Another object of my invention is to provide for automatically changing the speed of the roll tables concurrently with the change in speed of the reducing rolls, as the speed of the reducing rolls is varied, to maintain certain operating schedules and to accommodate the various shapes and thicknesses of metal which is being worked.

Other objects of my invention will be apparent from the following detailed description, taken in conjunction with the accompanying drawing, in which,

30 The single figure is a diagrammatic view of a rolling mill provided with the usual driving motors and control system, arranged for operation in accordance with the present invention.

35 Referring now to the drawing, the structure shown comprises a rolling mill 5 provided with reducing rolls 8 and feed rolls 9, in accordance with the usual practice.

In order to drive the reducing rolls 8, a 40 motor 12, having a separately excited field winding 13, is provided. As is usual practice, the speed of the reducing-roll motor 12 may be varied by the manipulation of a manually operated rheostat 14 which is 45 shown connected in series relation to the field winding 13. The reducing-roll motor 12 is shown connected to a supply source 15 and it may be controlled in any manner well known in the art.

50 In accordance with the usual practice, the

feed rolls 9 are actuated from a driven shaft 16 which is disposed to extend longitudinally to the roll table and provided with a plurality of beveled gear wheels which, as shown, mesh with beveled gear wheels 55 mounted on the table roller shafts.

The shaft 16 may be driven in any suitable manner and, in this particular instance, a separately excited motor 17 is provided which actuates the shaft 16 by means of the 60 gear train 18.

To control the operation of the motor 17, a controller 19 is provided which is interposed between the motor and a source of power supply, here shown as line conductors 20 and 21.

The field winding 22 of the auxiliary motor 17 is energized from an exciter 23 which is mechanically connected to a motor 24 by means of the shaft 25. A variable resistor 26 is connected in circuit with the field winding 22 for the purpose of partly controlling the energizing current which is further controlled by varying the generated voltage of the exciter 23.

The motor 24 is controlled, in a well known manner, by means of a "start" push-button switch 27 and a "stop" push-button switch 28, which, upon operation, establish or interrupt the operating circuit for a plurality of line switches 31 and 32 having contact members 33 to 36, inclusive.

In order to prevent the motor 24 from being connected to the line, unless the shunt field winding 37 is sufficiently energized to prevent excessive speeds, a relay 38 is provided. The relay 38 has a movable armature member 39 which is biased to the illustrated position by the coil spring 41 and is disposed to be actuated by an operating coil 42 which 90 is energized from the shunt-field circuit of the motor 24.

The contact members 43 of the relay 38 are adapted to interrupt the push-button-control circuit in case the field circuit of the motor 24 becomes de-energized and thus to prevent the establishment of an operating circuit for the line switches 31 and 32 unless the field winding 37 is properly energized.

A sectional starting resistor 40, which 100

connected in series with the armature of the motor 24, is controlled by electromagnetic switches 44 and 45. The switches 44 and 45 are respectively provided with actuating coils 46 and 47 which are adapted to be energized successively upon the operation of the line switch 31.

To provide for controlling the excitation of the field winding 48 of the exciter 23, a motor-actuated rheostat 49 is utilized. The rheostat 49 comprises a resistor 51 and a rotatable arm 52 which is adapted to exclude very small sections of the resistor 51 from the energizing circuit of the field winding 48 for a purpose which will be set forth more in detail hereinafter.

The rotatable arm 52 is actuated by means of a pilot motor 53 connected thereto through a worm and worm-wheel drive 54. The series field winding of the pilot motor 53 is composed of two sections 55 and 56 which are connected in series relation and adapted to be alternately energized to effect the rotation of the pilot motor in either direction.

In order to control the direction of rotation of the pilot motor 53, electromagnetic switches 57 and 58 are provided which may be utilized to reverse the line connections to the motor in a well known manner. Each of the switches 57 and 58 is connected in circuit with a section of the field winding and one of a pair of limit switches 59 and 61 which are disposed to be operated by the rotatable arm 52 as it approaches the end of its travel in either a clockwise or counter-clockwise direction.

The control of the motor-operated rheostat 49 may be effected manually or automatically to control the generated voltage of the exciter 23 and thereby the speed of the roll-table motor 17.

For manual control, push-button switches 62 and 63, each having a pair of closed and a pair of open contact members, are provided to establish operating circuits for the pilot-motor-control switches 57 and 58, in a manner which will be described in detail hereinafter.

The upper contact members of each of the push-button switches 62 and 63 are normally bridged by the movable elements and are connected in series relation, as shown. The bridged contact members are also connected in circuit with a voltage relay 68.

The voltage relay 68 has a movable member 69 biased toward the illustrated position by a suitable coil spring 71 and disposed to be actuated by the operating coil 73 to effect the engagement of contact members 72.

The operating coil 73 is connected in shunt relation to the field winding 13 of the reducing-roll motor 12 and is, therefore, responsive to the voltage impressed upon the field winding 13. The contacts of relay 68 are connected in the circuit which controls the operation of the motor-operated rheostat 49, but

since the operating coil 13 is connected as just stated, it is evident that the operating coil 73 must be energized and thus the contact members 72 engaged before operation of the motor-operated rheostat 49, can be obtained.

In the interest of economy and increased production in the rolling of metal by a rolling mill of this type, it is desirable to employ a control system which will function automatically to obtain the proper speed relation between the reducing rolls and the roll-tables.

In the rolling of different shapes and thicknesses of metal, it is necessary to frequently change the speed of the reducing rolls to obtain the proper rate of reduction and to maintain certain operating schedules.

As the speed of the reducing rolls is changed, in any suitable manner, it is desirable to also change the speed of the roll-tables to conform closely to the speed of the reducing rolls in order to prevent strains being imparted to the metal as it passes through the reducing rolls.

Heretofore, the practice has been to effect the change in speed of both the reducing rolls and the roll-tables by manual means. It will be readily understood that, when manual means for synchronizing speeds is resorted to, a great deal of time is expended in adjusting the speeds of the two separately driven parts of the mill, and that the utilization of speed-indicating instruments and the like is necessary. Therefore, to automatically effect a change in speed of the roll-table motors, concurrently with a change in speed of the reducing-roll motor, a fluttering-type relay 74 is interposed between the separately excited field winding 13 of the reducing-roll motor 12 and the exciter 23.

The relay 74, in the simple form which is utilized to illustrate the invention, is composed of a movable element 75 responsive to actuating coils 76 and 77 oppositely disposed to effect the movement of the movable member 75 either to the right or to the left, as shown.

The operating coil 76 of the relay 74 is connected across the armature of the exciter 23 and is, therefore, responsive to the generated voltage of the exciter 23, which is impressed upon the field winding 22 of the roll-table or auxiliary motor 17 and, consequently, operating coil 77 is responsive to the operating speed of motor 17, in a well-known manner.

The operating coil 77 of the oppositely disposed portion of relay 74 is connected in shunt relation to the separately excited shunt field winding 13 of the reducing-roll motor 12 and is, therefore, responsive to the voltage impressed on the field winding 13 and, subsequently, to the speed of the motor 12.

The movable member 75 is disposed to engage fixed contact fingers 78 and 79, as it is

actuated to the right or left-hand positions by the actuating coils 76 and 77, as described hereinbefore.

The fixed contact fingers 78 and 79 are, therefore, utilized for establishing an operating circuit to effect the operation of the motor-operated rheostat 49 to vary the generated voltage of the exciter 23.

It will be observed that a variable resistor 82 is in circuit with the operating coil 77 of the relay 74 and is, therefore, utilized for controlling the current flowing therein in the event that the normal voltage impressed upon the field winding 13 is greater than the voltage generated by the exciter 23 when the reducing rolls 8 and table rolls 9 are rotating at the same speed.

The operation of the rolling mill in accordance with the invention, will now be set forth.

In order to set the exciter 23 in operation, the "start" push-button switch 27 is closed to establish an operating circuit for the line switches 31 and 32 which extends from the positive conductor 21, through conductors 83 and 84, contact members 43 of the relay 38, conductor 85, the operating coils of switches 32 and 31, conductors 86 and 87, push-button switches 27 and 28 and conductor 88, to the negative line conductor 20. In this instance, it will be assumed that the relay 38 is sufficiently energized from the shunt field circuit of the motor 24 to cause the contact members 43 to engage and thus complete the push-button control circuit. The operating circuit of the relay 38 extends from the negative conductor 20, through conductor 89, field winding 37 of the motor 24, conductor 91, operating coil 42 of the relay 38 and conductors 84 and 83, to the positive line conductor 21.

In case the relay circuit is not properly established, the contact members 43 of relay 38 will remain in their open positions and it is impossible to establish the operating circuit for the line switches 31 and 32.

Upon the closure of the line switches 31 and 32, a holding circuit for them is established which may be traced from the negative line conductor 20, through conductor 88 and push-button 28, conductors 92, closed contact members 36, conductors 93 and 36, the operating coils of the line switches 31 and 32, conductor 85, contact members 43 of the relay 38 and conductors 84 and 83 to the positive line conductor 21. This permits the start push-button 27 to be released by the operator and maintains the line switches 31 and 32 in their closed positions.

The energizing circuit for the motor 24 extends from the positive line conductor 21, through conductor 118 and 83 to contact members 35 of the line switch 32, conductors 94, 95 and 96, the armature of the motor 24, conductors 97 and 98, resistor 40, con-

ductor 99, contact members 33 of the line switch 31 and conductor 101, to the negative line conductor 20.

The contact members 34 of the line switch 31, when in the closed position, establish an operating circuit for the resistor-short-circuiting contactor 44 which extends from the energized conductor 98, through the contact members 34, conductor 102, operating coil 46 of the contactor 44, to the energized conductor 95. The lower contact members of the contactor 44 are bridged, thereby short-circuiting the portion of the resistor 40 which accelerates the motor 24 a predetermined degree.

The upper and lower contact members of the contactor 44 are bridged at the same time, thereby establishing an operating circuit for the second resistor-short-circuiting contactor 45, which extends from the energized conductor 97, through conductor 103, upper contact members of the contactor 44, operating coil 47 and conductor 95 to the energized conductor 96. Upon the closure of the contactor 45, the second portion of the resistor 40 is short-circuited, which allows the motor 24 to accelerate to full speed.

Assuming now that the movable arm 52 of the motor-operated rheostat 49 is in the position illustrated, it establishes the proper circuit for energizing the field winding 48 of the exciter 23, which extends from the positive line conductor 21, through conductor 104, a portion of the resistor 51, conductor 105, field winding 48, conductors 106 and 101, to the negative line conductor 20.

Therefore, the proper voltage is built up in the exciter armature for energizing the field winding 22 on the auxiliary motor 17 by means of the circuit extending from the positive armature terminal of the exciter 23, through conductor 107, field winding 22, resistor 26 and conductor 108, to the negative armature terminal of the exciter 23. The roll table may now be put in operation by starting the motor 17 by means of the starter 19.

For the purpose of explanation, it will be assumed that the reducing-roll motor is completely deenergized and, therefore, the operating coil 77 is also deenergized and has no effect upon the movable member 75 of the relay 74.

As set forth hereinbefore, the operating coil 76 of the relay 74 is connected directly across the armature of the exciter 23 which generates sufficient voltage to energize the coil 76 which actuates the movable member 75 of the relay 74 to the left and establishes an operating circuit for the pilot-motor line switch 58. However, it will be observed that the contact members 72 of the relay 68, which are in the operating circuit of the line switch 57, are not in engagement and, therefore, it is impossible to complete the energizing circuit

for the pilot motor 53 until the field 13 of the reducing-roll motor 12 and, consequently, the coils 73 and 77 have been energized. The simultaneous energization of both the coils 73 and 77 insures that the proper degree of opposition to the coil 76 will be established to prevent the pilot-motor-operating circuit, which was established when the coil 76 was energized, from remaining closed long enough to effect the maximum travel of the rotatable arm 52 of the rheostat 49.

Since, in order to simplify the drawing, the control means for the reducing roll motor 12 is not shown, it will be assumed that it is operated to start the motor 12, after the energizing circuit for the field winding 13 has been established by the closure of the switch 80. The energizing circuit for the field winding 13 extends from the positive line conductor 21, through conductor 109, switch 80, variable resistor 14, conductor 111, field winding 13, conductors 112, 113 and 123, to negative line conductor 20.

When the field circuit of the reducing-roll motor 12 becomes energized, the operating coil 77 of the relay 74 is also energized through a circuit extending from the energized conductor 113, conductor 114, variable resistor 82, the operating coil 77 and conductor 115 to the energized conductor 111.

The coils 76 and 77 of the relay 74 are, in this instance, energized to a degree depending upon the relative values of voltage which is being generated by the exciter 23 and that which is being impressed upon the field winding 13.

In order to clearly explain the operation of the relay 74, it will first be assumed that the voltage impressed upon coil 77 is slightly greater than that generated by the exciter 23. In such event, the movable armature member 75 of the relay 74 is actuated to the right, into engagement with the fixed contact member 79. An operating circuit is established for the pilot-motor line switch 58, which extends from the positive conductor 21 through conductor 118, push-button switches 62 and 63, conductor 119, relay 68, contact member 79, conductors 121 and 122, the operating coil of the line switch 58 and conductor 123 to the negative line conductor 20.

Upon the closing of the pilot-motor line switch 58, an energizing circuit for the pilot motor 53 is established which extends from the positive conductor 21, through conductor 104, the armature of the pilot motor 53, field winding 55, limit switch 59, conductor 60, switch 58, conductor 123, to the negative line conductor 20.

The energizing circuit thus established causes the pilot motor 53 to operate in a direction to actuate the rotatable arm 52 counter-clockwise, thus decreasing the amount of the resistor 51 which is connected in series

with the field winding 48 of the exciter 23. In such manner, the exciter voltage is increased, thus increasing the energizing current flowing in the operating coil 76 of the relay 74 and, consequently, tending to actuate the movable member 75 to the left or toward the fixed contact member 78.

It will be readily understood that, so long as the voltage impressed upon the operating coil 77 is sufficient to maintain the movable contact member 75 in engagement with the fixed contact member 79, the operating circuit for the pilot motor 53 will be maintained.

The generated voltage of the exciter 23 will, therefore, gradually increase, as herein before set forth, until such time as the pull of the coil 76 equals that of the electromagnet 77. In this event, a state of equilibrium will exist, and the movable contact member 75 will, consequently, return to the mid-position and interrupt the operating circuit for the pilot-motor line switch 58.

At this point in the cycle of operation, the rotatable arm 52 or the motor-operated rheostat 49 is stopped in some such position as shown, and then an appreciable portion of the resistor 51 will have been gradually removed from the field circuit of the exciter 23.

It will now be noted that the voltage impressed upon the field winding 22 of the auxiliary or roll-table motor 17 has been increased and, consequently, a reduction in speed of the motor 17 is obtained which causes the feed rolls 9 to revolve at approximately the same speed as that of the reducing rolls 8.

Let it be further assumed that the operator desires to increase the speed of the reducing-roll motor 12 which may be accomplished by manipulating the variable resistor 14 to reduce the voltage impressed upon the field winding 13.

In such event, the current flowing in the operating coil of the coil 77 will be reduced to a value lower than the current flowing in the operating coil 76 and the movable member 75 will be actuated to the left into engagement with the fixed contact finger 78. The operation of the member 75 establishes an operating circuit for the pilot-motor line switch 57, which extends from the positive conductor 21, through conductor 118, push-button switches 62 and 63, conductor 119, contact member 72 of the relay 68, the fixed contact member 78, conductors 120 and 124, the operating coil of the line switch 57 and conductor 123, to the negative line conductor 20.

Upon the closure of the line switch 57, an energizing circuit for the pilot motor 53 is established which extends from the positive conductor 21, through conductor 104, the armature of the pilot-motor 53, field winding 56, conductor 125, limit switch 61, line switch 57 and conductor 123, to the negative line conductor 20. It will be noted that, in this case, the second portion of the series field

winding 56 of the pilot-motor 53 was included in the motor circuit and that it was energized in such direction as to cause the reverse operation of the pilot motor 53, therefore by actuating the rotative arm 52 clockwise to gradually increase the amount of the resistor 51 contained in the field circuit of the exciter 23.

It can be readily understood that the exciter voltage will be decreased to a point where the voltage impressed upon the coil 76 will equal that which is impressed upon the opposing coil 77, and, consequently, a state of equilibrium will again be obtained, and the pilot-motor circuit be deenergized in the manner described hereinbefore.

As the voltage generated by the exciter 23 is gradually decreased, the voltage impressed upon the field winding 22 of the auxiliary motor 17 is decreased, and consequently, the speed of the auxiliary motor 17 is increased to raise the speed of the table rollers 9 to that of the increased reducing roll speed.

As mentioned hereinbefore, the motor-operated rheostat, operating in conjunction with the relay 74, may be controlled manually by means of the push-button switches 62 and 63.

In the event that the operator wishes to increase or reduce the speed of the auxiliary motor 17 for any reason, this may be accomplished by depressing the fast push-button 62 or the slow push-button 63.

In order to clearly illustrate the facility with which this control system may be adapted for either automatic or manual speed regulation between the reducing-roll motor 12 and the auxiliary or roll-table motor 17, it will be assumed that if the operator wishes to decrease the speed of the table rolls 9 below that of the reducing rolls 8, he will proceed in the following manner.

The push-button switch 63 is depressed, which bridges the lower contact members and establishes an operating circuit for the pilot motor line switch 58, extending from the positive line conductor 21, through conductor 118, lower contact members of the push-button switch 63, conductor 122, operating coil 50 of the switch 58 and conductor 123, to the negative line conductor 20.

Upon the closure of the switch 58, an energizing circuit for the pilot-motor 53 is established in exactly the same manner described hereinbefore and, the rotatable arm 52 is revolved counter-clockwise to increase the generated voltage of the exciter 23 and, consequently, to decrease the speed of the auxiliary motor 17.

Since certain changes may be made in the above described system and different embodiments of the invention may be made without departing from the scope thereof, it is intended that all the matter contained in the above description or shown in the accompany-

ing drawing shall be interpreted as illustrative and not in a limiting sense.

I claim as my invention:

1. In a control system for rolling mills provided with reducing rolls and roll tables, in combination, a motor for actuating the reducing rolls, an auxiliary motor for actuating the roll tables, means for varying the excitation of the motor driving the reducing rolls to vary the speed of the reducing rolls, and means responsive to changes in excitation of said reducing-roll driving motor to vary the speed of the auxiliary motor, to prevent the application of undesirable strains to the metal as it passes through the rolling mill.

2. In a control system for rolling mills provided with reducing rolls and roll tables, in combination, a motor for actuating the reducing-rolls, an auxiliary motor for actuating the roll tables, means for varying the excitation of the motor driving the reducing rolls, and electrically-operable means responsive to the degree of excitation of said reducing-roll driving motor to vary the speed of the auxiliary motor, thereby to prevent the application of undesirable strains to the metal as it passes through the rolling mill.

3. In a control system for rolling mills provided with reducing rolls and roll tables, in combination, a motor for actuating the reducing rolls, an auxiliary motor for actuating the roll tables, means for varying the speed of the motor driving the reducing rolls, a relay responsive to changes in speed of the reducing-roll driving motor and means controlled by said relay for varying the speed of the auxiliary motor to prevent the application of undesirable strains to the metal as it passes through the rolling mill.

4. In a control system for rolling mills provided with reducing rolls and roll tables, in combination, a motor for actuating the reducing rolls, an auxiliary motor for actuating the roll tables, means for varying the speed of the motor driving the reducing rolls, a relay responsive to changes in speed of the reducing-roll driving motor, a motor-generator set for controlling the speed of the auxiliary motor, and means responsive to the action of the relay for controlling the excitation of the generator of the motor-generator set and, therefore, the speed of the auxiliary motor to prevent the application of undesirable strains to the metal as it passes through the rolling mill.

5. In a control system for rolling mills provided with reducing rolls, and roll tables, in combination, a motor for actuating the reducing rolls, said motor having a field winding, means for energizing the field winding, an auxiliary motor for actuating the roll tables, said motor having a field winding, a motor-generator set for exciting the field winding of the auxiliary motor, and means in-

- terposed between the motor driving the reducing rolls and the motor-generator set for controlling the excitation of the generator, said means being responsive to the change in 5 excitation of the motor driving the reducing rolls and thereby controlling the generator voltage to vary the speed of the auxiliary motor to prevent the applications of undesirable strains to the metal as it passes through 10 the rolling mill.
6. In a control system for rolling mills provided with reducing rolls and roll tables, in combination, a motor for actuating the reducing rolls, said motor having a field winding, means for energizing the field winding, an auxiliary motor for actuating the roll tables, said motor having a field winding, a generator for exciting the field winding of the auxiliary motor, a motor-actuated rheostat for controlling the generator voltage, and a relay interposed between the generator armature and the field of the reducing-roll driving motor, said relay being responsive to changes in the excitation of the reducing-roll driving motor and the generator voltage to control the operation of the motor-actuated rheostat to vary the excitation of the generator and, consequently, the speed of the auxiliary motor in accordance with 20 changes in speed of the reducing-roll driving motor to prevent the application of undesirable strains to the metal as it passes through 25 the rolling mills.
7. In a control system for rolling mills provided with reducing rolls and roll tables, in combination, a motor for actuating the reducing rolls, said motor having a field winding, means for energizing the field winding, an auxiliary motor for actuating the roll 30 tables, said motor having a field winding, a generator for exciting the field winding of the auxiliary motor, means for varying the generator voltage, and a relay having a plurality of operating coils and a balanced armature disposed to be actuated by the operating coils, one of said coils being connected across the generator armature, another coil being connected across the field of the reducing-roll driving motor, said relay being responsive to 35 the generator voltage and the field voltage of the reducing-roll driving motor, respectively, to control the means for varying the generator voltage, thereby varying the speed of the auxiliary motor in accordance with any 40 change made in the speed of the reducing-roll driving motor to prevent the applications of undesirable strains to the metal as it passes through 45 the rolling mill.
8. In a control system for rolling mills 50 provided with reducing rolls and roll tables, in combination, a motor for actuating the reducing rolls, an auxiliary motor for actuating the roll tables, means for varying the speed of the motor driving the reducing rolls, 55 means for controlling the speed of the auxil- 60
- iary motor, a relay responsive to changes in excitation of the reducing-roll motor and adapted to control the speed-controlling means for the auxiliary motor and means responsive to the excitation voltage of the reducing-roll motor interposed between the control means for the auxiliary motor and the relay, and adapted to control the said auxiliary motor-control means to prevent any change of speed of the auxiliary motor 65 unless the field of the reducing-roll driving motor is being excited.
- In testimony whereof, I have hereunto subscribed my name this 26th day of September, 1927.
